ENVELOPE OPENER

Eldon W. Adams, 1982 Cameo Drive, Campbell, Calif.
Filed Sept. 18, 1961, Ser. No. 138,864
5 Claims. (Cl. 30—294)

This invention relates to envelope openers and more particularly to a device for cutting one edge of an envelope passed therethrough.

It is one object of this invention to provide a letter opening device which is simple in construction, economical to manufacture and highly efficient in use.

It is another object to provide an envelope opener adapted to be held in the palm of one hand while an envelope is guided therethrough with the other hand to cut a slit along one edge of such envelope.

Another object is to provide an envelope opener having a blade disposed in a guideway along which one edge may be guided for cutting a slit in such envelope. In this connection it is a further object to provide in such an envelope opener a feature tending to maintain the envelope in the guideway to facilitate a uniform cut parallel to the edge of the envelope so guided. It is still another object to provide such a device with a yieldable blade pressured to make a minimum slit in such an envelope.

These and other objects and advantages of the present invention will become apparent from a reading of the following description in the light of the accompanying drawing in which:

FIG. 1 is a side view of an envelope opener embodying the present invention and partially broken away for the purpose of illustrating the same.

FIG. 2 is an end view of FIG. 1 as seen from the right side of FIG. 1.

FIG. 3 is a perspective view of the envelope opener of FIGS. 1 and 2; and

FIG. 4 is a fragmentary vertical section of FIG. 1 taken along line 4—4 thereof and at slightly enlarged scale with respect thereto.

As best seen in FIG. 1 the device 10 comprises a block type body 11 which may be made of wood, plastic or any other suitable material. The body 11 is so formed and proportioned as to fit into the palm or grip of a human hand leaving the other hand free to maneuver and/or manipulate an envelope relative to the device 10 in a manner later to be explained.

The block 11 is provided with a kerf-like groove 12 so dimensioned as to receive one edge *e* of an envelope *E* as illustrated in FIGS. 3 and 4. The groove 12 is of a width sufficient to receive a double thickness of paper such as would be presented by the flap *f* and back *b* of a conventional letter sized envelope *E*. As will be observed in FIG. 4 the width of the groove 12 is such as to receive double thicknesses of even heavier paper such as would be used in manila envelopes.

The groove 12 formed in the body 11 presents a flat side surface 13 upon which one side of the envelope can rest and a flat base end surface 14 against which the folded edge *e* of the envelope *E* can bear. In this manner the groove 12 in the block body 11 provides a guideway for receiving and guiding an envelope in flat, parallel relation to the side (13) and base (14) surfaces formed in the block body 11.

Within the block body 11 is a spring urged blade 15 so disposed as to have one end of its cutting edge extended into the guideway groove 12. More specifically, the block body is recessed as at 16 to provide a chamber for the blade 15. The bottom of the recess 16 is a flat surface 17 disposed on a plane common to the flat base surface 14 of the guideway groove 12. The recess 16 is offset slightly from the guideway groove

2

12 by a relatively narrow partition 18 so as to provide a continuous upper surface 19 to the groove through which an envelope is guided. However, the groove 12 communicates with the recess or chamber 16 via a passage 20 through which one end 21 of the blade 15 can extend. The back face or wall 22 of passage 20 is on the same plane as the base surface 14 of the groove 12 as well as the bottom flat surface 17 of the recess chamber 16. Thus all surfaces 14, 17 and 22 provide a common surface 23 against which the blade 15 can lie.

The blade 15 is mounted for pivotal movement on a pin in the form of a headed wood screw 24 which extends through a bore in the blade. The pivot pin or screw 24 is disposed a greater distance from the end 21 of the blade than it is from the base surface 13 of the groove 12. In this manner the blade is floatingly arranged within the recess 16 at an angle relative to the guideway groove 12 so that only one triangular corner 26 of the blade extends through the passage 20 and the balance of the cutting edge of the blade is out of contact with the body 11 other than where the tip of the triangular corner 26 engages the flat side wall 13 of the guideway 12.

The blade 15 has one edge ground to provide a bevel 27 on that side of the blade which faces the common surface 23 upon which the blade is mounted. This beveled edge 27 is at right angles with respect to the end 21 of the blade and forms therewith the triangular corner 26 hereinbefore mentioned. The blade 15 tends to bear down against the base surface 13 of the guideway 12 so that the triangular corner 26 will engage an envelope as it moves along the guideway 12. Means 28 is provided for yieldably urging the blade 15 toward cutting position relative to an envelope passing through guideway 12.

The means 28 in the present disclosure consists of a spring 29 mounted within a second recess in the form of a bore 33 in the body block 11. The spring 29 bears against the upper edge 30 of blade 15 so as to urge the blade toward cutting position. A bearing plug 31 is mounted on the inner end of the spring 29 and has a rounded face bearing tangentially against the upper edge 30 of the blade 15 so as to minimize friction and assure constant bearing against the pivoted blade.

The upper end of spring 29 is seated in a recessed end of a screw plug 30 having threaded connection to the recess or bore 33 formed in the block 11. By this arrangement the compressive strength of the spring 29 can be controlled and adjusted to bear against the blade 15 at the desired pressure. In this manner the blade 15 has a three point suspension within the body 11, namely, at the pin 24; the yieldable spring 29; and at the tip of the triangular corner engaging the flat side surface 13 of the groove 12 or the double edge of an envelope as it passes through the groove 12.

According to the foregoing arrangement it is contemplated that an envelope *E* be inserted into the guideway 12 on that side of the blade having the beveled edge 27 first to engage the envelope as seen in FIGS. 1 and 3 the entrance side of the guideway is designated 35. To facilitate admittance of the envelope *E* into the entrance side 35 of the guideway 12, the latter is provided with flared upper and lower edges 19' and 13' respectively. These edges 19' and 13' are beveled such as to guide one edge *e* of an envelope funnel fashion into the base of the guideway groove 12. This guidance takes place automatically as the leading edge *L* of an envelope is inserted into the guideway entrance 35 and the edge *e* of the envelope brought into parallel relation and engagement with the flat end surface 14 of the groove 12.

As the envelope is now moved relatively with respect to the block 11 the leading edge L of the envelope first engages the pointed end 26 of the blade 15. With the spring 29 properly pressured, the blade 15 will yield somewhat, i.e. swing clockwise about its pivotal mounting 24, so that the pointed end of the blade cuts into the first layer (flap f) of the envelope.

Now as the envelope and block 11 are moved relatively advancing the envelope past the blade, a slit S is cut into that layer of the envelope so engaged, flap f in the illustration of FIG. 3.

It is important to note that the beveled edge 27 of blade 15 is so disposed as to cooperate with the guideway 12 in tending to urge the envelope inwardly thereof. In other words, the beveled edge 27 affords a cam-like action which forces the edge e of the envelope toward the flat surface 14 of the groove 12 to thereby automatically maintain the edge e of the envelope in parallel relation thereto.

When the envelope has thus been moved relatively with respect to the block 11 the blade 15 will have completely scribed a slit S across the entire flap f (or whatever layer is engaged by the blade) to open the envelope.

It should be understood that although the yieldable blade can be pressured such as to effect a complete cut through both layers of paper engaged thereby such operation results in the nuisance of long strips of severed paper having to be removed and picked up. By the pressure arrangement afforded in the present invention the blade 15 is yieldable to cut a slit in only one layer of an envelope to open the same. This eliminates any severed strips and simplifies the handling of envelopes.

While I have described my new envelope opener in specific detail it will be appreciated that the same may be modified, altered and/or varied without departing from the spirit of my invention therein. I therefore desire to avail myself of all modifications, alterations and/or variations of construction as may fairly come within the purview of the appended claims.

What I claim as new and desire to protect by Letters Patent is:

1. An envelope opener comprising a block body having a guideway formed along one straight edge thereof for receiving one edge of an envelope, a recessed chamber formed in said block having a bottom wall surface on a plane common to the base surface of said guideway, a spring urged blade pivotally mounted on the bottom wall surface of said recessed chamber and at an angle relative to said guideway for presenting one triangular corner of said blade to said guideway, said blade having a beveled edge on that side thereof facing said plane common to said bottom wall and base surface of said chamber and guideway, tending to urge that edge of an envelope engaged by said blade toward the base surface of said guideway.

2. An envelope opener comprising a block body having a guideway along one straight edge thereof provided with a base surface against which one edge of an envelope to be opened can bear, a blade mounting surface in said block body on a plane common to said base surface of said guideway, a blade pivotally mounted on said blade mounting surface and having its cutting edge disposed at an angle relative to said guideway, and spring means between said blade and block body for yieldably urging said blade into said guideway for cutting a slit in an envelope guided therethrough, said cutting edge being beveled on that side only of said blade exposed toward said plane which is common to said base surface of said guideway for urging said one edge of an envelope to be opened

into parallel relation to said base surface of said guideway.

3. An envelope opener comprising a block body having an open guideway formed therein providing a flat side wall upon which one side of an envelope can rest and a flat base against which the folded edge of such envelope can bear during relative movement of such envelope along said guideway, said body having a recess chamber formed therein on that side of said guideway opposite said flat side wall thereof, a passage formed in said block body between said recess chamber and said guideway, a blade arranged in said recess chamber and having one triangular corner adjacent its cutting edge extending through said passage and into said guideway for engagement with said flat side wall thereof, a mounting pin in said recess and extending through said blade for pivotally supporting said blade within said recess with the cutting edge of said blade out of contact with said block body other than where the said triangular corner of said blade engages the flat side wall of said guideway, and spring means mounted within said block body yieldably engaging said blade on that side thereof relative to said mounting pin which is above the said triangular corner of said blade for urging the latter into yielding engagement with the said flat side wall of said guideway.

4. An envelope opener comprising a block body adapted to be held in the palm of a human hand, a guideway formed on said block for receiving and guiding one edge of an envelope therealong, said body having a recess chamber formed therein diagonally of said guideway and communicating with the latter, a blade arranged in said recess chamber with one triangular corner of said blade extending into said guideway, said blade having an aperture substantially midway thereof, a pin extending through the aperture in said blade and secured to said block body for supporting said blade within said recess with its cutting edge out of contact with said block body except where the triangular corner of said blade extends into said guideway for engaging an envelope guided therethrough, a second recess formed in said block body above that end of said blade which overlies the triangular corner thereof, and spring means seated in said second recess pressing against said blade for yieldably urging the triangular corner of the latter toward said guideway for cutting a slit in the said one edge of an envelope guided therethrough.

5. An envelope opener comprising a block body having a kerf-like guideway along one straight edge thereof provided with a flat wall surface upon which one side of an envelope can rest and a base surface against which one folded edge of an envelope to be opened can bear, a blade mounting surface in said block body on a plane common to said base surface in said guideway, a beveled edge blade pivotally mounted on said blade mounting surface, said blade having one corner of its beveled edge normally disposed in said guideway in engagement with said flat wall surface of said guideway, and spring means within said block body bearing against said blade whereby said blade yields to cut only one thickness of the folded edge of an envelope guided through said guideway.
